QUENCHED HYDROFLUORIC ACID
CONVERSION

Joe E. Penick, Woodbury, N. J., assignor to Socony-Vacuum Oil Company, Incorporated, a corporation of New York

Application August 17, 1950, Serial No. 179,924

4 Claims. (Cl. 196—50)

1

The present invention relates to the conversion of hydrocarbons employing hydrofluoric acid as a catalyst and, more particularly to the conversion in liquid phase of mixtures of hydrocarbons having relatively low octane numbers to mixtures of hydrocarbons having relatively high octane numbers; the conversion being carried out in the presence of hydrogen fluoride and at elevated temperatures.

While the conversion of hydrocarbons employing hydrofluoric acid as a catalyst has been disclosed in various patents, notably U. S. Patents Nos. 2,403,649; 2,454,615; 2,450,588; and 2,449,463, it is preferred to subject the hydrocarbon mixture to be converted to the conditions described in co-pending application Serial No. 94,955, filed May 24, 1949, now Patent No. 2,606,860 in the name of Joe E. Penick. The present application is a continuation-in-part of the aforesaid application Serial No. 94,955 and provides for improved results therewith.

As disclosed in the aforesaid pending application, the conversion of hydrocarbon mixtures having low octane numbers to hydrocarbon mixtures having relatively high octane numbers is carried out by contacting such hydrocarbon mixtures, naphthas for example, with hydrogen fluoride in the liquid state in amounts greater than that required to saturate the hydrocarbon charge with hydrogen fluoride but not more than in the ratio of two volumes of hydrofluoric acid to one volume of hydrocarbon charge stock at temperatures of the order of 270° F. to 470° F. and preferably in the range of 320° F. to 450° F.

It has been found that operational difficulties can be avoided and improved yields can be obtained by quenching the reaction mixture before separating the acid phase from the hydrocarbon phase.

It has been discovered that (1) the mutual solubilities of hydrogen fluoride and saturated hydrocarbons increase logarithmically with increasing temperature and (2) the coefficient of thermal expansion for hydrogen fluoride is greater than that for hydrocarbons so that as the temperature is increased the density of hydrogen fluoride decreases more rapidly than the density of hydrocarbons. At temperatures in the range of 300° F. to 450° F. the density of hydrogen fluoride is in the range of densities of hydrocarbons so that the density of hydrogen fluoride under these conditions may be the same, even less or only slightly higher than the density of the hydrocarbon phase. Consequently, a clean separa-

2

tion of the hydrogen fluoride phase from the hydrocarbon phase in this temperature range is impossible.

The relation between the density of hydrogen fluoride and the density of hydrocarbon mixtures as influenced by the temperature is clearly demonstrated by the curves of Figure I. It is manifest that at temperatures between about 300° F. and about 450° F. the density of hydrogen fluoride is such as to preclude gravity separation of hydrogen fluoride from a hydrocarbon mixture. For example, at 300° F. hydrogen fluoride has a density of about 6.16 pounds per gallon and the densities of hydrocarbon mixtures having gravities of 5 45°, 52° and 54° A. P. I. are respectively, 5.84, 5.58 and 5.49 pounds per gallon. Furthermore, hydrogen fluoride has the same density as a 45° A. P. I. hydrocarbon mixture at 360° F., as a 52° A. P. I. hydrocarbon mixture at 412° F., and as a 54° A. P. I. hydrocarbon mixture at about 434° F.

Whenever an attempt is made to separate hydrogen fluoride from a hydrocarbon phase at temperatures above about 250° F., say at 300° F., separation of the two phases is so poor that it is impossible to achieve the steady operation so necessary to a conversion process involving continuous operation. For example, the amount of hydrogen fluoride in the hydrocarbon phase becomes so large that the main fractionator has insufficient capacity to obtain the desired fractionation and the fractionator bottoms contain considerable amounts of both hydrogen fluoride and tar. At the same time the interface between the hydrocarbon mixture and the hydrogen fluoride in the settler (as determined by electrical conductivity measurements) is less distinct and even disappears completely at times.

As a result of the increased solubility of hydrogen fluoride in hydrocarbon mixtures at high temperatures (300° F. and greater) a greater amount of heat is required. The hydrogen fluoride, not separated from the hydrocarbon phase by gravity separation must be removed by vaporization in the main fractionator and the hydrogen fluoride stripper. Since the hydrocarbon phase leaving the settler operating at temperatures above about 250° F. will contain from 5 to 40 per cent hydrogen fluoride, the quantity of heat required to vaporize this amount of hydrogen fluoride is quite large and often exceeds all the other heat requirements for the process. The heat used in vaporizing dissolved and/or entrained hydrogen fluoride from the hydrocarbon phase is wasted because nothing is gained from the va-

porization except freeing the hydrocarbon mixture of hydrogen fluoride.

The hydrogen fluoride dissolved and/or entrained in the hydrocarbon phase coming from a gravity separation at temperatures above about 250° F. carries substantial amounts of tar. When the hydrogen fluoride is vaporized in the main fractionator the tar remains in the bottoms and is recycled in solution in the hydrocarbon recycle stock. This tar is readily extracted from the recycle stock when the recycle stock contacts the hydrogen fluoride in the reactor. This dilutes the hydrogen fluoride and reduces its effectiveness as a catalyst. Since tar dissolved in the hydrogen fluoride in the hydrocarbon phase coming from a settler operating at temperatures above about 250° F. cannot be withdrawn from the process save by fractionation of the bottoms of the main fractionator, i. e., a second vaporization operation, it is manifest that in the absence of quenching prior to gravity separation of the hydrogen fluoride phase from the hydrocarbon phase vaporization does not serve to improve in any way the effectiveness of the catalyst. This problem can become so great due to the increase in the quantity of hydrogen fluoride and tar dissolved therein present in the hydrocarbon phase and the resultant increase in the internal recycle of the tar that the process becomes inoperative.

When the gravity separation of the hydrogen fluoride phase and the hydrocarbon phase takes place at temperatures above about 250° F. the hydrocarbon phase leaving the settler contains more than 2 per cent of dissolved hydrogen fluoride. The vaporization of such large quantities of hydrogen fluoride in the fractionator results in excessive corrosion of the fractionator.

When the gravity separation of hydrogen fluoride from a hydrocarbon mixture takes place at temperatures in excess of about 250° F., 5 to 20 per cent and even more of the hydrocarbon phase is dissolved or entrained in the hydrogen fluoride phase. The dissolved or entrained hydrocarbon material is lost as tar in the acid regenerator and the volume of material which must be handled to process a given weight of hydrogen fluoride is increased. Both of these end results are undesirable from a standpoint of economics.

From the foregoing discussion of the disadvantages arising from attempting gravity separation of hydrogen fluoride from hydrocarbon mixtures at temperatures above about 250° F., it will be manifest to those skilled in the art that the present invention provides an improvement in prior art hydrocarbon conversion processes employing hydrogen fluoride as a catalyst and reaction temperatures in excess of about 250° F. The aforesaid improvement, broadly stated, comprises carrying out a gravity separation of hydrogen fluoride from the hydrocarbon phase of the reaction mixture at temperatures not greater than about 250° F. and preferably at temperatures of about 150° F. to about 200° F.

The sequence of operations described in co-pending application Serial No. 94,955 can be modified by interposing a cooler between the reactor 13 and the settler 16 of Figure I of that disclosure. However it is preferred to modify the procedure therein described in a manner such as illustrated in either Figure II or Figure III of the drawings of the present application in which Figure I is a graph showing the relation between temperature and the density of hydro-

gen fluoride and the densities of various hydrocarbon mixtures;

Figure II is a flowsheet, in more or less diagrammatic form, of one embodiment of the present invention;

Figure III is a flowsheet, in more or less diagrammatic form, of another embodiment of the present invention, and

Figure IV is a flowsheet, in more or less diagrammatic form, showing the application of the separation of the hydrogen fluoride phase from the hydrocarbon phase at temperatures not greater than 250° F. and preferably below 200° F. to the invention described in the co-pending application Serial No. 94,955.

Illustrative broadly of the effect of separating liquid hydrogen fluoride from a liquid hydrocarbon phase at temperatures not greater than 250° F. and preferably at temperatures not greater than 200° F. and especially at temperatures of about 150° to about 200° F. is the following data.

A hydrocarbon conversion unit wherein the hydrocarbon conversion took place at a temperature above 300° F. and the gravity separation of the hydrogen fluoride and hydrocarbon phases took place at about 290° F. was operated for about 6 hours. The hydrocarbon phase passed through the settler at the rate of 23.2 gallons per hour and contained 5.6 weight per cent hydrogen fluoride. In other words, $5.71 \times .056 = 0.32$ pound of hydrogen fluoride were dissolved or entrained in a gallon of hydrocarbon phase when the separation was carried out at 290° F. On the other hand, when the separation of the liquid hydrogen fluoride phase from the liquid hydrocarbon phase was carried out at 200° F. the liquid hydrocarbon phase contained only 0.06 pound of hydrogen fluoride per gallon. In other words, separation of the liquid hydrogen fluoride phase from the liquid hydrocarbon phase at a temperature not greater than 250° F. and preferably at a temperature of 200° F. or less resulted in a reduction of 81 per cent in the amount of hydrogen fluoride dissolved or entrained in the hydrocarbon phase. In addition, it was possible at the lower separation temperature to treat about 15 volume per cent more hydrocarbon in the same equipment.

In accordance with the principles of the present invention hydrocarbons can be subjected to conversion in accordance with operations schematically illustrated in Figures II, III and IV. Referring to Figure II, it will be seen that fresh hydrocarbon feed, for example a naphtha of low octane number, is withdrawn from a source not shown through lines 1 and 2 by pump 3. The charge or feed is passed through line 4 to reactor 5. Fresh hydrogen fluoride is withdrawn from a source not shown through line 6 by pump 7 and discharged through line 8 into line 9. Recycle hydrogen fluoride is withdrawn from settler 10 through line 11 by pump 12 and discharged into line 9. At point 13 on line 9 the fresh hydrogen fluoride joins the recycle hydrogen fluoride and the mixed fresh and recycle hydrogen fluoride passes through a heat exchanger 14 or other means for raising the temperature of the stream of hydrogen fluoride. The heated stream of hydrogen fluoride leaves heater 14 by pipe 15 which joins line 4 at point 16.

A secondary recycle stream of hydrogen fluoride is withdrawn from stripper overhead ac-

cumulator 17 through line 18 by pump 19 and discharged through line 20 into pipe 4 at point 16. The mixture of hydrogen fluoride and hydrocarbon passes upwardly through reactor 5, operated at temperatures of about 270° F. to about 470° F. and preferably of about 320° F. to about 450° F. and pressure sufficient to maintain the hydrogen fluoride in the liquid state and preferably at a pressure at least 125 p. s. i. greater than the pressure of the reaction, and through conduit 21 to heat exchanger or cooler 22 in which the temperature of the liquid hydrocarbon-hydrogen fluoride stream is reduced to not greater than about 250° F. and preferably to about 200° F. or less. The liquid hydrocarbon-liquid hydrogen fluoride stream after cooling to at least 250° F. and preferably after cooling to at least 200° F. passes through pipe 23 into settler 10.

In settler 10 the liquid hydrogen fluoride (when the temperature is below about 250° F.) forms the lower stratum and the liquid hydrocarbons the upper stratum or phase.

The liquid hydrocarbons leave the settler 10 through line 24 and pass therethrough to the hydrogen fluoride stripper 25. In stripper 25 the hydrogen fluoride, light hydrocarbons and non-condensable gases escape as overhead through line 26, cooler 27 and line 28 to stripper overhead accumulator 17. Vent gas escapes from accumulator 17 through line 29.

The hydrocarbon bottoms in stripper 25 flow through line 30 to fractionator 31 wherein an overhead hydrocarbon product is separated from a recycle bottoms product. The overhead product leaves fractionator 31 by pipe 32, cooler 33 and line 34 to storage or other use.

The hydrocarbon recycle bottoms are withdrawn from fractionator 31 through lines 35 and 2 by pump 3. At point 36 on line 2 fresh hydrocarbon feed joins the recycle bottoms.

At times it will be desirable to bleed some hydrogen fluoride continuously or intermittently from the hydrogen fluoride recycle stream and send the spent hydrogen fluoride to the hydrogen fluoride regenerator. To this end spent hydrogen fluoride, i. e., an acid stream containing less than 96 per cent hydrogen fluoride and preferably less than 90 per cent hydrogen fluoride is withdrawn from line 11 at some point say 37 and passed through line 38 to the hydrogen fluoride regenerator.

Since the flowsheet of Figure II is essentially diagrammatic in nature the necessary and desirable valves have not been illustrated. Furthermore, the location of such valves being a matter of choice, those skilled in the art are able to place the valves in the desirable necessary positions.

Figure III is a diagrammatic illustration of a modification of the sequence of operations illustrated in Figure II which nevertheless is illustrative of the spirit of the present invention. The primary difference between the sequence of operations illustrated in Figure III and that illustrated in Figure II is the use of the fresh hydrocarbon feed as a reflux in the fractionator. In other respects the operations are the same.

Thus, fresh hydrocarbon feed, for example coker gasoline is withdrawn from a source not shown through line 41 and introduced into fractionator 42 as a reflux. When the fresh feed has components having boiling ranges of the same order as the overhead of fractionator 42 those components are distilled off with the reaction product overhead. The bottoms of the hydro-

carbon phase of the reaction mixture together with the higher boiling constituents of the fresh hydrocarbon feed is withdrawn from fractionator 42 through line 43 by pump 44 and discharged into reactor 45 through line 46. Recycle hydrogen fluoride forms the bottom layer of the reaction mixture in settler 47 when the contents of the settler are at a temperature of 250° F. or less and preferably at a temperature of 200° F. or less. The recycle hydrogen fluoride is withdrawn from settler 47 through pipe 48 by pump 49. At a point intermediate settler 47 and pump 49, a portion of the recycle hydrogen fluoride is continuously or intermittently withdrawn through conduit 50 for regeneration in a hydrogen fluoride regenerator (not shown).

Recycle hydrogen fluoride is discharged by pump 49 into line 51 leading into heater 52. At a point intermediate pump 49 and heater 52, fresh hydrogen fluoride drawn through line 53 by pump 54 from the hydrogen fluoride regenerator (not shown) joins the stream of recycle hydrogen fluoride. The recycle hydrogen fluoride and fresh hydrogen fluoride passes from heater 52 through line 55 to reactor 45.

Some recycle hydrogen fluoride accumulates in stripper overhead accumulator 56. This recycle hydrogen fluoride is withdrawn from accumulator 56 through line 57 by pump 58 and discharged through line 59 into reactor 45. (It will be noted that the streams in lines 46, 55 and 59 are all joined before entering reactor 45.) The reaction mixture of liquid hydrogen fluoride and hydrocarbons passes upwardly through reactor 45 at elevated temperatures in excess of 250° F., usually at temperatures above 300° F., and at a pressure sufficient to maintain the hydrogen fluoride in the liquid state. However, it is preferred to employ pressures at least 125, and preferably 150 p. s. i. greater than the vapor pressure of the reaction mixture at the reaction temperature.

The reaction mixture leaves reactor 45 through pipe 60, passes through cooler 61, in which the stream is cooled to at least 250° F. and preferably to 200° F. or less, and line 62 to settler 47. The hydrocarbon phase leaves the settler through line 63 and passes to hydrogen fluoride stripper 64.

In stripper 64 dissolved and/or entrained hydrogen fluoride is taken as an overhead together with non-condensable gases such as hydrogen, nitrogen, hydrogen sulfide, carbon dioxide and light hydrocarbons such as methane and ethane. The hydrogen fluoride and non-condensable gases pass as overhead via line 65, cooler 66 and line 67 to stripper overhead accumulator 56 from which the non-condensable gases are removed by pipe 68.

The bottoms of stripper 64 is the hydrocarbon phase substantially free from hydrogen fluoride. The bottoms is removed from stripper 64 through conduit 69 as feed for fractionator 42. The overhead for fractionator 42 is removed therefrom through pipe 70 and cooler 71 to storage or further treatment.

There is some difference between the characteristics of the product produced by following the sequence of operations illustrated by Figure II and those of the product produced in accordance with the flowsheet of Figure III. These differences are illustrated by the data presented in Table I.

TABLE I

Hydrogen fluoride conversion of coker gasoline with separation of hydrogen fluoride at about 200° F.

¹ Volume 300° EP Gasoline produced/hydrocarbon charge to reactor X100.

In general, the present method provides for the treatment of mixtures of hydrocarbons, especially naphthas, with hydrogen fluoride in liquid state in amounts greater than that required to saturate the hydrocarbon charge with hydrogen fluoride and not more than in the ratio of two volumes of hydrofluoric acid to one volume of hydrocarbon charge stock at temperatures of the order of 270° F. to 470° F. and preferably in the range of 320° F. to 450° F.

It has been found that the hydrofluoric acid should contain at least 4 per cent by weight and not more than about 40 per cent by weight of acid soluble oil and not more than about 10 per cent of water.

It has been found that, generally, the hydrocarbon stock at room temperature is saturated with hydrogen fluoride when a concentration of about 0.5 per cent hydrogen fluoride is attained. Consequently, an amount of hydrogen fluoride in excess of about 0.5 per cent by weight of the hydrocarbon charge is in excess of that amount required to saturate the hydrocarbon charge.

Although any mixture of hydrocarbons can be treated, the present method is very readily illustrated by discussion of the treatment of naphthas. Thus, for example, the treatment of naphthas having a boiling range of about 250° to 400° F. and naphthas having a boiling range of about 315° to 400° F. will be used to illustrate the basic principles of the present method of converting hydrocarbons.

As shown in a more or less diagrammatic manner in Figure IV, the fresh hydrocarbon charge from a source not shown is passed by means of line 80 through heat exchanger 81 and line 82 to reactor 83. Liquid hydrogen fluoride or hydrofluoric acid is introduced into reactor 83 by conduit 84 under the pressure required by the pressure in reactor 83. Reactor 83 is of sufficient capacity to provide a residence time sufficient that a conversion of less than 40 per cent to liquid products having a 90 per cent point below the 10 per cent point of the charge stock is obtained at temperatures of 270° F. to 470° F. and at pressures sufficient to maintain the reactants in the liquid state at the reaction temperature.

The reaction mixture comprising reactants, catalyst and reaction products is passed via line 85 to cooler 85A and thence to settler 86. In cooler 85A the temperature of the reaction mix-

ture is reduced to not greater than about 250° F. and preferably to a temperature not greater than about 200° F. In settler 86 the hydrogen fluoride phase is the lower phase and is drawn-off through line 87 by pump 88.

The hydrocarbon products being lighter than the hydrofluoric acid phase at temperatures below about 250° F. form the upper layer in settler 86 and are withdrawn through line 89, pressure reducing valve 90 and line 91 to the main fractionating tower 92 in which the hydrocarbon products, whose 90 per cent point is at least below the 10 per cent point of the charge stock and saturated with hydrogen fluoride, are withdrawn through line 93, heat exchanger 94 and line 95 to the hydrogen fluoride stripper 96. The remaining higher boiling hydrocarbons are withdrawn from fractionating column 92 through line 97 by pump 98 and recycled to reactor 83 through lines 99 and 82.

In the stripper 96 hydrogen fluoride and light hydrocarbons are taken as overhead and passed through line 100, heat exchanger 101 and line 102 to settler 103 in which the hydrogen fluoride forms the lower liquid phase and the light hydrocarbons the upper liquid phase.

The hydrocarbon phase in settler 103 is returned through line 104 to stripper 96 to serve as reflux while the hydrogen fluoride is withdrawn from settler 103 through line 105 to line 106.

The hydrogen fluoride phase withdrawn from settler 86 through line 87 in part is transferred to the hydrogen fluoride regenerator 107 through line 110 under the control of valve 110A. In regenerator 107 hydrogen fluoride is taken as an overhead through line 108 and heat exchanger 109 and with the hydrogen fluoride from settler 103 returned through lines 106 and 84 to the reactor 83. Tar is withdrawn from regenerator 107 through line 112.

Returning now to the hydrogen fluoride stripping operation, the overhead from stripper 96 is hydrogen fluoride and light fractions of the desired product. This overhead is withdrawn as described hereinbefore through line 100. The bottoms, i. e., the desired product having a 90 per cent point lower than the 10 per cent point of the charge stock is withdrawn from stripper 96 through line 111 to storage or for further treatment or other use as the situation requires.

The foregoing has been a description of the general operation of the present method. However, certain factors affect the results of the present method of converting hydrocarbons and require discussion. Thus, for example, it has been established that the acid to hydrocarbon; i. e., hydrofluoric acid to charge stock ratio has a marked effect upon the amount of high boiling or tarry material produced. This is aptly illustrated by the curves of Figure V. The materials treated to illustrate this effect were two naphthas; one having a boiling range of 250°-400° F. and the other having a boiling range of 315°-400° F. The curves of Figure V establish that as the ratio of hydrogen fluoride to charge stock is increased from about 0.4 to 5.0 volumes of hydrofluoric acid per volume of charge stock the ratio of converted raffinate; i. e., material having a 90 per cent point below the 10 per cent point of the charge stock, to organic material soluble in the hydrofluoric acid phase; i. e., tarry material, decreases from 6 to 1 to 1 to 1. In other words, when treating a charge stock at a given temperature and under a pressure sufficient to maintain the reactants in the liquid phase, the ratio of desired products to undesirable products decreases as the ratio of hydrofluoric acid to charge stock decreases. Thus, at a HF:HC ratio of 0.4-0.5 volumes to one volume, the volume of the hydrocarbon product was 6 times the volume of the acid soluble oil. In contrast, when 3 volumes of hydrofluoric acid were used per one volume of charge, the ratio of desired product to acid soluble oil was 1 to 1. The foregoing can be stated in another manner. When the hydrofluoric acid to charge stock ratio was 0.4-0.5:1 the desired product was about 86 per cent of the charge stock converted and the acid soluble oil about 14 per cent. However, when the hydrofluoric acid to charge stock ratio was 3:1, about 54 per cent of the charge was converted to desired product and about 46 per cent to acid soluble oil.

The curves in Figure VI establish that in the treatment of naphthas as the ratio of acid to charge stock is increased from about 0.5 to about 4.6 to 1 (by volume), the ultimate conversion decreases from about 90 per cent to about 55 per cent.

The foregoing leads to the expression of the preferred conditions as those in which the ratio of hydrofluoric acid or hydrogen fluoride to charge stock is not greater than about 2.0 to 1 and not less than an excess of that amount of hydrogen fluoride required to saturate the charge stock therewith.

A further modification of the basic concept is control of the water and soluble oil content of the catalytic hydrofluoric acid. It has been found that improved results are obtained when the acid contains at least 4 per cent by weight of organic material soluble in the acid catalyst and termed herein acid soluble oil. Figures VII and VIII illustrate the fact that with fresh hydrofluoric acid about 9.2 per cent of the charge is converted to organic material soluble in the acid; i. e., acid soluble oil although that represents only about 4 weight per cent of the acid phase. When that acid is recycled only about 8 weight per cent of the charge is converted to acid soluble oil in the second pass and about 5 weight per cent in the third and subsequent passes, although the total amount of acid soluble oil reaches about 9 weight per cent of the acid phase in the fourth and subsequent passes. In other words, when

the hydrofluoric acid contains about 8 to about 10 weight per cent of acid soluble oil, the conversion of charge stock to acid soluble oil is a minimum.

The results produced by the basic method of operation can be still further improved by carrying out the conversion in the liquid phase at a pressure more than at least 150 p. s. i. greater than the vapor pressure of the products of conversion at the reaction temperature. Thus, for example, when treating a heavy naphtha from a Mid-Continent crude, it was found that the octane number of the gasoline produced could be raised about 7 numbers by resorting to this variation in operation. These data are presented in tabular form as follows:

TABLE II

Charge stock	314°-400° F., heavy naphtha.
Reaction temperature	340° F.
Contact time	About 7 minutes.
HF/HC ratio (volume)	0.5:1
Vapor pressure of conversion products at reaction temperature	780 p. s. i.

Reaction Pressure	1,600 p. s. i.	900 p. s. i.
Pressure Differential	820 p. s. i.	120 p. s. i.
Charge Stock Octane Number	18.0	18.0
Octane Number of Conversion	77.2	70.0
Gasoline		
Ultimate Yield, Vol. Percent of Charge	80	68

It is manifest that not only is the improvement in octane number markedly greater but the ultimate yield of gasoline is about 18 volume per cent greater as a result of operating at a reaction pressure greater than about 150 p. s. i. greater than the vapor pressure of the conversion products.

The residence time for the conversion reaction varies with the temperature and in general is less the higher the temperature within the interval 270° F. to 470° F. The preferred conditions are a reaction temperature of about 300° F. to 450° F., a residence time sufficient to secure not more than about 40 volume per cent conversion to products having a 90 per cent point lower than the 10 per cent point of the charge stock and preferably a residence time sufficient to obtain only about 20 to 30 per cent conversion to products having a 90 per cent point lower than the 10 per cent point of the charge stock. In general, a residence time of not more than 20 minutes and preferably of the order of 2 to 10 minutes dependent upon the reaction temperature is desirable. With the reaction conditions described hereinbefore, satisfactory results will be obtained employing at least sufficient hydrofluoric acid to form a second liquid phase; i. e., an amount in excess of that required to saturate the charge stock with hydrofluoric acid and not more than about 2.0 volumes of hydrofluoric acid per volume of charge stock and preferably about 0.4 volume to about 1.5 volumes of hydrofluoric acid per volume of charge stock. The results described herein can only be obtained when the reactants are in the liquid state. Consequently, the conversion reaction must be carried out at a pressure at least sufficient at the reaction temperature to maintain liquid state conditions and preferably at least 150 pounds per square inch (p. s. i.) higher than the vapor pressure of the effluent from the reactor at the reaction temperature.

While the present conversion method may be carried out with total recycle or without recycle of the hydrofluoric acid, it is preferred to recycle

at least 25 per cent of the hydrofluoric acid. Similarly, while 100 per cent hydrofluoric acid may be used and the concentration of hydrogen fluoride in the catalytic acid should be more than 50 per cent with a maximum of 10 per cent of water, it is preferred that the acid catalyst contain not more than 5 per cent of water and at least 4 per cent of soluble organic material herein termed acid soluble oil. Thus, acid catalyst containing not more than 5 per cent water and preferably less than 3 per cent water and having a titratable acidity of at least 50 per cent to about 90 per cent hydrogen fluoride gives satisfactory results.

I claim:

1. A method of raising the octane rating of naphtha which comprises contacting naphtha with an amount of hydrogen fluoride in excess of that required to saturate said naphtha and not more than about 2.0 volumes of hydrogen fluoride per volume of naphtha, said hydrogen fluoride containing about 4 to about 10 per cent acid soluble oil, at a reaction temperature of about 270° to about 470° F., at a pressure at least 125 p. s. i. greater than the vapor pressure of the reaction mixture at the aforesaid reaction temperature and for not more than about 20 minutes, cooling the liquid reaction mixture to about 150° to about 250° F., and separating a hydrocarbon conversion product having a 90 per cent point below the 10 per cent point of said charge naphtha and containing less than 5 per cent hydrogen fluoride from a liquid hydrogen fluoride phase.

2. A method of raising the octane number of naphtha which comprises contacting naphtha with a liquid catalyst comprising hydrogen fluoride about 50 to about 90 per cent, about 4 to about 10 per cent of acid soluble oil and the balance, to make 100 per cent, water, in the ratio of about 0.4 to about 2.0 volumes of catalyst per volume of naphtha, to form a reaction mixture, holding said reaction mixture at a reaction temperature of about 270° to about 470° F. for about 2 to about 10 minutes at a pressure at least 125 p. s. i. greater than the vapor pressure of said

reaction mixture at said reaction temperature, cooling said reaction mixture to about 150° to about 250° F., and separating a hydrocarbon conversion product having a 90 per cent point below the 10 per cent point of said charge naphtha and containing less than 5 per cent hydrogen fluoride from a liquid hydrogen fluoride phase.

3. A method of raising the octane number of naphtha which comprises contacting naphtha with a liquid catalyst comprising about 8 to about 10 per cent acid soluble oil, about 3 to about 5 per cent water and the balance to make 100 per cent hydrogen fluoride in the ratio of about 0.4 to about 1.5 volumes of hydrogen fluoride per volume of naphtha to form a reaction mixture, maintaining said reaction mixture at a reaction temperature of about 270° to about 470° F. and at a pressure at least 125 p. s. i. greater than the vapor pressure of said reaction mixture for about 2 to about 10 minutes, cooling said reaction mixture to about 150° to about 250° F., and separating a hydrocarbon conversion product having a 90 per cent point below the 10 per cent point of said charge naphtha and containing not more than 2 per cent hydrogen fluoride from a liquid hydrogen fluoride phase.

15 4. The method of raising the octane number of naphtha as set forth and described in claim 3 wherein the reaction temperature is about 300° to about 450° F., the reaction pressure is about 150 to about 820 p. s. i. greater than the vapor pressure of the reaction mixture, and the reaction mixture is cooled to about 150° to about 200° F.
